Clinton A. Runyon, Jr., Chicago, Ill.

Application September 4, 1948, Serial No. 148,486

Term of patent 14 years

(Cl. D56—4)

To all whom it may concern:

Be it known that I, Clinton A. Runyon, Jr., a citizen of the United States, residing at city of Chicago, county of Cook, and State of Illinois, have invented a new, original, and ornamental Design for a Mouthpiece for Wind Instruments, of which the following is a specification, reference being had to the accompanying drawing, forming a part thereof.

Fig. 1 is a plan view of a mouthpiece for wind instruments showing my new design;

Fig. 2 is a side view;

Fig. 3 is a plan view opposite that shown in Fig. 1;

Fig. 4 is an end view thereof as seen from the right of Fig. 2; and

Fig. 5 is an end view opposite that shown in Fig. 4.

I claim:

The ornamental design for a mouthpiece for wind instruments, substantially as shown.

CLINTON A. RUNYON, JR.
